UNITED STATES PATENT OFFICE.

ANNA HIEBL AND ELIZABETH BARRY, OF NORTH BERGEN, NEW JERSEY.

BOUDOIR CAP.

Application filed April 14, 1924. Serial No. 706,391.

To all whom it may concern:

Be it known that we, ANNA HIEBL and ELIZABETH BARRY, citizens of Germany and the United States, respectively, residing at 5 North Bergen, in the county of Hudson and State of New Jersey, have invented new and useful Improvements in Boudoir Caps, of which the following is a specification.

This invention relates to caps and more 10 particularly to ladies' boudoir caps.

The principal object of the invention resides in the provision of a boudoir cap which may be placed in a relatively flat condition whereby the entire surface of the 15 cap may be easily accessible when it is desired to iron the same during the laundering process.

A further object of the invention is to provide a boudoir cap which may be adjusted to the head of the wearer by means of a non-elastic element and after the initial adjustment, the cap may be easily removed or applied without affecting the adjustment.

A still further object of the invention is 25 to provide a boudoir cap which is simple in construction, cheap of manufacture and comfortable when in position upon the head of the wearer.

With these and other objects in view, 30 the invention resides in certain novel construction and combination and arrangement of parts, the essential features of which are hereinafter fully described, are particularly pointed out in the appended claims, and are 35 illustrated in the accompanying drawing, in which:—

Figure 1 is a perspective view of our improved boudoir cap.

Figure 2 is an enlarged perspective view 40 showing the cap in a relatively flat condition.

Figure 3 is an enlarged fragmentary horizontal sectional view on the line 3—3 of Figure 1.

Heretofore great difficulty has been experienced in the laundering of boudoir caps as it has been the practice of constructing the same by placing an elastic element in the edge of the cap to render the same adjustable to the head of various persons. This elastic tends to gather the body of the cap so that when ironing, it is a practical impossibility to iron the cap free from all wrinkles and creases. It is therefore our 55 intention to overcome these objections and

to permit of the easy application or removal of the cap to the head.

Referring more particularly to the drawing, the reference numeral 10 designates the cap in its entirety and which includes a 60 body portion 11 of any suitable material. The front of the body portion is provided with an upturned portion 12 which portion terminates at the sides of the body portion and merely serves to add to the attractive- 65 ness of the cap. The body portion is slit as at 13 from its edge adjacent the ends of the upturned portion and the edge between the slits is turned under and stitched as at 14 to provide a hem 15. Secured to 70 each end of the hem portion and enclosed therein are draw strings 16, the free ends of which project through an opening 17 in the outside wall of the hem midway between the slits. The opposite side edges of 75 the slit portions have secured thereto, a female element 18 and a co-acting male element 19, such as a snap fastener and which elements are adapted to close the slits when the cap is in position upon the head 80 as will be readily understood. Whereas, there has been shown a snap fastener for securing the walls of the slit together, we wish it to be understood that a button and button hole construction might be substi- 85 tuted therefor without departing from the spirit of the invention.

In practice, the cap is applied to the head of the wearer by passing the same there-over with the slits opened and with the 90 draw strings untied. When in proper position upon the head the fastening elements are brought in their co-acting position and the draw strings are pulled to their ad-justed position after which they are tied 95 or knotted. It will be seen that the mate-rial between the slits is gathered when the strings are in their adjusted position and will give the appearance of an elastic ad-justing means. Should it be desired to re-move the cap from the head, the male and female elements are separated to open the slit which will give an increased diameter to the body of the cap and permit the same to be easily removed without in any way 105 disturbing or affecting the headdress of the wearer. It will be seen that after the initial adjustment by means of the draw string, it is unnecessary to untie the same as only the slits need be opened. When laundering the 110

cap the draw strings are untied and the slits opened which will permit the cap to be spread to a comparatively flat condition such as that shown in Figure 2 of the drawing. 5 This will permit the sad iron to pass over the complete surface of the cap whereby it is possible to launder the same in a neat and attractive manner.

While we have described what we deem to be the most desirable embodiment of our invention, it is obvious that many of the details may be varied without in any way departing from the spirit of our invention, and we therefore do not limit ourselves to the exact details of construction herein set forth nor to anything less than the whole of our invention limited only by the appended claims.

What is claimed as new is:—
20 1. A boudoir cap comprising a body por-

tion having its edge provided with spaced slits, co-acting elements for closing said slits, and adjusting means between said slits, said last means including a hem, and a pair of draw strings each having one of their ends secured to the body portion adjacent a slit and the free ends extending out of an opening in said hem midway between the slits. 25

2. A boudoir cap comprising a body portion having its edge provided with spaced slits, co-acting elements for closing said slits, the edge between said slits being hemmed, and a non-elastic element in the hem for adjusting the diameter of the body portion at the edge thereof. 30

In testimony whereof we have affixed our signatures.

ANNA HIEBL.
ELIZABETH BARRY.
